MECHANICAL INTERLOCK FOR ENGINE SELF-STARTERS.

1,214,048.

Specification of Letters Patent.

Patented Jan. 30, 1917.

Application filed September 28, 1912. Serial No. 722,847.

To all whom it may concern:

Be it known that I, ALDEN L. McMURTRY, a citizen of the United States, and a resident of Sound Beach, in the county of Fairfield, 5 and State of Connecticut, have invented certain new and useful Improvements in Mechanical Interlocks for Engine Self-Starters, of which the following is a specification, reference being had to the accompanying 10 drawings, forming a part thereof.

This invention relates to a mechanism for insuring the correct adjustment of the ignition system and the throttle of an internal combustion engine when a self starting device is thrown into action, and its object is 15 to automatically insure the proper action of the engine when it is started with such an arrangement.

I will describe my invention in the following specification and point out the novel features in appended claims.

Referring to the drawings, Figure 1 is a diagrammatic side elevation of a mechanism which embodies my invention. Fig. 2 is a 25 side elevation of one of the parts of the apparatus illustrated in Fig. 1 showing it as modified to coöperate with another form of self-starter. A detail of construction is shown in Fig. 3, this being an elevation on 30 an enlarged scale, of the slip-joint which is used in connection with the other parts of the mechanism. In Fig. 4 the switch which controls the ignition system is shown in front elevation together with the arrangement which is used to actuate it. Figs. 5 35 and 6 are bottom plan views of the handle of the switch and its actuating rod showing them in different operative positions.

Like characters of reference designate corresponding parts in all the figures.

The dash-board of an automobile is shown in section at 10. On this is mounted the control-lever 11 of a self-starter. Apparatus for starting internal combustion engines 45 without manual effort are well known and as they form no part of my invention they are not illustrated. But those in common use depend upon the use of a supply of energy, either electricity or fluid pressure. In 50 Fig. 1 the control lever 11 is a part of an electric switch which is adapted to be pushed into a stationary contact 12 to close a circuit for the purpose of causing the self-starting apparatus to act. Or if desired this

control lever may be the handle of a valve 55 for controlling the flow of fluid through a pipe for the same purpose. It is shown as such at 11^a in Fig. 2.

A rod 13 connects the control lever with one arm 14 of a three-arm lever which is 60 pivotally supported at 15. To the opposite arm 16 is connected a plunger 17 which is used to actuate a switch 40 in a manner which will be specifically described later. The third arm 18 is connected by a rod 19 65 with one arm of a bell crank lever which is pivotally supported at 20. The other arm of this bell-crank lever is connected by a rod 21 with a slideable block 22. In this block are two longitudinal holes. Through one of 70 these holes passes a rod 23 from the adjusting lever 24 of the engine throttle, which is shown in the drawings in its open position. A pin 25 projects from rod 23 through a slot 26 in the block 22 parallel with the hole 75 through which the rod 23 passes.

27 is the rod by means of which the usual manual control of the throttle is effected. The rod 23 passes through a lug on the end of this control rod and a compression spring 80 28 is interposed between this lug and a collar 29 on the end of the rod 23.

30 designates a magneto which comprises the usual distributor the adjustment of which is accomplished by moving a lever 34. 85

33 is a rod which is connected with lever 34 and which passes through the other hole in the block 22. A pin 35 projects from this rod through a slot 36 in the slideable block. A rod 37 runs to the point from 90 which the usual manual control of the distributor is made. On the end of this rod is a lug through which the rod 33 runs and a compression spring 38 is interposed between this lug and a collar 39 on the end of rod 33. 95

The switch 40 is provided with a lever 41 which when depending vertically is in its off position. When moved to the left, it is arranged to connect the magneto with the engine's ignition system. When moved 100 to the right the magneto is disconnected and a battery is connected with the ignition circuits. This too is well known and so the circuits are not shown.

On the back of the switch-lever is a projecting shoulder 42 which is arranged to contact with the plunger 17. This plunger slides through a bushing 43 one end of

which forms a projecting lip 44. On the plunger itself is a fixed lug 45 and a pawl 46 pivoted at 47 and provided with a heavier lower portion 48 which is arranged as I shall show, to engage with the lip 44.

The various parts of this apparatus have been pointed out and I will now describe its operation: When a combustion engine is to be started, it is important that the throttle be not closed so that the engine can get its required supply of gas, that the spark distributor be not advanced otherwise "back-kicking" will result, and that the ignition system be connected with the battery supply rather than with the magneto until the latter becomes driven by the engine at a high enough rate of speed to generate sufficient power to energize the ignition system. Even a skilled mechanician may forget to make all of these important adjustments before attempting to start an engine. When the engine is to be started by manual effort it is easier to remember these details than it is when a self-starter is used and one merely has to close a switch or open a valve to set the engine in motion. By the use of this invention all of the three important adjustments set forth are made automatically without interfering with the usual manual adjustments which may be made either before or after the use of the self-starter. When the operator pushes the control lever 11 of the self-starter forward, its movement is transmitted through the mechanical connections shown and described, to the plunger 17 which is slid backward and to the block 22 which is slid forward. The throttle-lever 24 and the distributor lever 34 are shown in their open and retard positions respectively. When in this position the forward movement of the block 22 will have no effect upon either of them. But if the throttle is closed and the distributor is advanced, their levers will be over toward their positions indicated in dotted lines at 24^A and 34^A respectively. In such case the pins 25 and 35 will be engaged by the ends of the slots 26 and 36 as block 22 moves forward, and the levers pushed thereby into their desired positions. It is obvious that either or both of these adjustments may take place and that both the throttle and the distributor are brought to the desired positions whether they had been moved little or much from them. If the throttle had been closed by a movement of the rod 27 to the rear, it still may be opened by the forward movement of the block 22 as in such cases the rod 27 could remain stationary and the rod 23 moved relatively, merely compressing the spring 28. The same thing is true of the adjustment of the distributor by means of rod 37. Thus the automatic adjustment of these elements takes place without affecting the manual

adjustments thereof. After the engine has been started and the control lever 11 moved back to its initial position, the parts described are restored to their original positions so that the usual manipulations for adjustment may be made as readily as they could if my mechanisms were not present. When the plunger moves backward, the lug 45 engages the shoulder 42 on the switch lever and pushes the latter from whatever position it happens to be in, into its "battery" position. Therefore this movement of the plunger insures the connection of the battery with the engine's ignition system during the time the self-starter is in action. During the backward movement of the plunger, the pawl 46 will assume the position in which it is shown in Fig. 5 on the side of shoulder 42 opposite the lug 45. Now when the control lever is moved back again the consequent forward movement of the plunger will draw the switch arm with it, on account of the engagement of the pawl 46 with the shoulder 42, until the switch is moved to its "magneto" position. Then the lower end 48 of the pawl will ride up onto the lip 44 of the bushing, which will move the other end of the pawl down out of engagement with the shoulder 42, as is illustrated in Fig. 6. Then the switch lever 41 may be moved by hand at will to its "off" position or back to its battery position. It may be seen then that when the self-starter is used, the engine adjustments must be properly made, and that the mechanism which is provided for the purpose of automatically insuring the desired positioning of these adjustments, comes into use only when the self-starter is in action, and that after the self-starter has performed its function and is thrown out of action, the apparatus herein described in no way hinders or affects the mechanisms for making the usual adjustments of these parts of the engine.

What I claim is:

1. In combination with an internal combustion engine and a self starter therefor, a control lever, a throttle for the engine and a mechanical connection between said lever and the throttle whereby the throttle may be adjusted by the starting movement of the control lever of the starting device.

2. In combination with an internal combustion engine and a self starter therefor, a control lever, a plunger mechanically connected with said lever and a switch adapted to be adjusted by the movement of the plunger in response to the control lever of the starting device.

3. In combination with an internal combustion engine and a self starter therefor, a control lever, a switch, a switch lever, and a plunger mechanically connected with the control lever and arranged to be moved

thereby in opposite directions and an engaging device on said plunger for moving the switch lever in opposite directions.

4. In combination with an internal combustion engine and a self starter therefor, a control lever, a switch, a switch lever capable of manual actuation, and means actuated by the movement of the control lever in opposite directions for moving the switch lever in opposite directions without interfering with subsequent manual actuation of the switch lever.

5. In combination with an internal combustion engine and a self starter therefor, a control lever, a switch having a "battery" position, an "off" position, and a "magneto" position, a switch lever and means actuated by a movement of the switch lever in a direction to set the self starter in action to move the switch into its "battery" position, and by a movement of the control lever in an opposite direction to move the switch into its "magneto" position.

6. In combination with an internal combustion engine and a self starter therefor, a control lever, a switch having a "battery" position, an "off" position, and a "magneto" position, a switch lever, means actuated by a movement of the control lever in a direction to set the self starter in action to push the switch into its "battery" position, and by a movement of the control lever in an opposite direction to pull the switch lever into its "magneto" position and to release the switch lever so that it subsequently may be moved manually.

7. In combination with an internal combustion engine and a self starter therefor, a control lever, a slideable plunger a mechanical connection between said lever and plunger, whereby the movements of the lever are transmitted to the plunger, a switch having a "battery" position, an "off" position and a "magneto" position and a switch lever; a projection on the plunger arranged to engage the switch lever to push the switch into its "battery" position upon a movement of the control lever to set the self starter into action, a pivoted pawl on said plunger arranged to engage the switch lever and to pull the switch into its "magneto" position upon an opposite movement of the control lever and means for tripping the pawl out of engagement with the switch lever so that the switch subsequently may be manipulated.

8. In combination with an internal combustion engine and a self starter therefor, a control lever, a distributor having an adjusting arm, means for manually moving said arm to accomplish the usual adjustments of the distributor and a mechanical connection between said lever and said arm by which the movement of the control lever to set the self starter in action is transmitted to the

distributor arm without interfering with the manually actuated adjusting means.

9. In combination with an internal combustion engine and a self starter therefor, a control lever, a throttle having an adjusting arm, means for manually moving said arm to accomplish the usual adjustments of the throttle and a mechanical connection between said lever and said arm by which the movement of the control lever to set the self starter in action is transmitted to the throttle arm without interfering with the manually actuated adjusting means.

10. In combination with an internal combustion engine and a self starter therefor, a control lever, a distributor and a throttle, connection between said lever and the distributor and throttle whereby the distributor and throttle may be adjusted by the starting movement of the control lever of the starting device.

11. In combination with an internal combustion engine and a self starter therefor, a control lever, a distributor having an adjusting arm and a throttle having an adjusting arm, connections between said lever and the arms of the distributor and the throttle whereby the distributor arm and the throttle arm may be moved in the one direction by the movement of the control lever to set the starting device in action and whereby the control lever of the starting device may be moved in the opposite direction without affecting the distributor arm or the throttle arm.

12. In combination with an internal combustion engine and a self starter therefor, a control lever, a distributor, a throttle and a switch, connections between said lever and the distributor, the throttle and the switch, whereby the distributor, the throttle and the switch, may be adjusted by the starting movement of the control lever of the starting device.

13. In combination with an internal combustion engine and a self starter therefor, a control lever, a distributor, a throttle and a switch, connections between said lever and the distributor, the throttle and the switch, whereby the distributor, the throttle and the switch, may be adjusted by the movement of the control lever to set the starting device in action and whereby the opposite movement of the control lever adjusts the switch without affecting the distributor or the throttle.

14. In combination with an internal combustion engine and a self starter therefor, a control lever, a distributor having an adjusting arm, means for manually moving said arm to accomplish the usual adjustments of the distributor, a throttle having an adjusting arm, means for manually adjusting the throttle arm to accomplish the usual adjustments of the throttle and me-

chanical connections between the lever and both of said adjusting arms by which the movement of the control lever to set the self starter in action is transmitted to the 5 distributor arm and to the throttle arm without interfering with the manually actuated adjusting means.

15. In combination with an internal combustion engine and a self starter therefor, 10 a control lever, a distributer having an adjusting arm, means for manually moving said arm to accomplish the usual adjustments of the distributer, a throttle having an adjusting arm, means for manually adjusting the throttle arm to accomplish the usual adjustments of the throttle and mechanical connections between the lever and both of said adjusting arms by which the movement of the control lever to set the self 15 starter in action is transmitted to the distributer arm and to the throttle arm without interfering with the manually actuated adjusting means; a switch, a switch lever capable of manual actuation and means 20 actuated by the movement of the control lever in opposite directions for moving the switch lever in opposite directions without interfering with subsequent manual actuation of the switch lever.
- 25 16. In combination with an internal combustion engine and a self starter therefor, a control lever, a distributer having an adjusting arm, means for manually moving said arm to accomplish the usual adjustment of the

ments of the distributer, a throttle having 35 an adjusting arm, means for manually adjusting the throttle arm to accomplish the usual adjustments of the throttle and mechanical connections between the lever and both of said adjusting arms by which the 40 movement of the control lever to set the self starter in action is transmitted to the distributer arm and to the throttle arm without interfering with the manually actuated adjusting means; a slidable plunger, a mechanical connection between said lever and plunger whereby the movements of the lever are transmitted to the plunger, a switch having a "battery" position, an "off" position and a "magneto" position and a switch 45 lever; a projection and a plunger arranged to engage the switch lever to push the switch into its "battery" position upon a movement of the control lever to set the self starter into action, a pivoted pawl on said plunger arranged to engage the switch lever and to pull the switch into its "magneto" position 50 upon an opposite movement of the control lever and means for tripping the pawl out of engagement with the switch lever so the switch subsequently may be manipulated.

55 In witness whereof, I have hereunto set my hand this 23 day of September in the year 1912.

ALDEN L. McMURTRY.
